CLAIM

The ornamental design for a cover for earphone charging case or the like, as shown and described.

DESCRIPTION

FIG. 1 is a front, top, and right-side perspective view of a cover for earphone charging case or the like showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, bottom, and right-side perspective view thereof; and,

FIG. 9 is a back, bottom, and right-side perspective view thereof.

The interior of the cover for earphone charging case or the like, seen through the opening in FIGS. 1 and 6, forms no part of the claimed design.

1 Claim, 5 Drawing Sheets
